CONVEYER CHAIN AND FLIGHT

Nils D. Levin, Columbus, Ohio, assignor to The Jeffrey Manufacturing Company, Columbus, Ohio, a corporation of Ohio

Application November 5, 1930, Serial No. 493,661

11 Claims. (Cl. 198—168)

The present invention relates to a novel chain and flight combination for conveyers and also to the flight and chain construction per se.

According to the embodiment of the invention to be hereinafter described, the chain is adapted to be circulated over a conveyer base-plate with the advancing and returning runs of the chain arranged side by side and guided on the top of the plate, certain of the chain links being so formed as to be engaged with and secured to the conveyer flights in a novel manner. The flights themselves, in addition to the novel means provided for engagement with the above mentioned links, are of a novel form which enables them to be engaged most effectively and to disrupt, if necessary, material to be gathered by the conveyer. To this latter end, the flights comprise as usual a lower edge or surface adapted to be moved over the base-plate surface in scraping relation thereto, the flight being attached at one end to the chain with its other end projecting freely over the base-plate. At its top the flight is provided with a fin or plate portion lying in a plane at substantially right angles to the longitudinal line of the chain and declined from the chain to the free flight extremity. The upper edge of the fin is provided with serrations which enable the flight to engage material to be moved with a superior disruptive action.

Without further discussion of general features of the invention, I shall proceed to describe an illustrative embodiment thereof in connection with the accompanying drawing of which:

Figure 1 is a plan view of a section of the conveyer chain with the flight attached thereto.

Figure 2 is an elevation of the devices shown in Figure 1;

Figure 3 is a transverse section of a gathering conveyer equipped with the chain and flights of the present invention; and

Figure 4 is a central longitudinal section of a modified form of flight.

The present application is a continuation in part of my copending application Serial No. 448,626, filed April 30, 1930, in the United States Patent Office, Figure 3 being a section through the gathering conveyer shown and described in that application, the flights alone being of modified construction.

Referring to the drawings, the conveyer chain comprises alternated block links 5 and plate links 6. The block links consist of two articulated sections 7 and 8 connected together by means of a pintle 9. Sections 7 and 8 are provided at their ends with bores perpendicular to pintle 9

and adapted to receive pintles 10 and 11 which connect the ends of adjacent block link sections with the plates 12 and 13 of the plate links. Plates 12 and 13 are identical, and since plate 12 is shown to advantage in Figure 1, this plate 60 will be particularly described.

At one side of the chain, plate 12 is provided with a rectangularly and outwardly projecting flange 14 whose extremities are bevelled as may be seen in Figure 1. At the other side of the 65 chain, plate 12 projects a substantial distance beyond the block links and is provided with perforations as at 15 and 16. It will be noted that the pintle receiving apertures thus lie between flange 14 and apertures 15 and 16. It will be further apparent that plate 12 is in the form of a rectangle having rounded corners, and that the pintle receiving apertures and apertures 15 and 16 are at the points of an imaginary rectangle whose major sides are parallel with the line of flange 14. Plate 70 13, as may be seen from Figure 2 has a flange 17 similar to flange 14, but projecting in the opposite direction from the latter.

Referring to Figure 3, reference numeral 18 designates a base-plate having mounted at either 80 side of its central longitudinal line chain guiding devices comprising upper and lower strips 19 and 20 provided with opposed grooves 21 and 22 in which flanges 14 and 17 are adapted to be engaged for guidance. With the flanges so engaged, 85 pintles 10 and 11 assuming a perpendicular relation to the base-plate so as to permit flexing of the chain in a plane parallel to the base-plate, while pintles 9 are in parallel relation to the base-plate so as to permit flexing of the chain in a 90 plane perpendicular to the base-plate. The size of the plates 12 and 13 is such as to position apertures 15 and 16, which are in alignment with similar apertures of plate 13, outside and clear of guide members 19 and 20 so that the apertures 95 may receive flight securing pins or bolts 23 and 24 in spaced relation to the guide members.

The new flight generally indicated at 25 comprises a substantially triangular pyramidal, hollow body portion 26 open at one side so that the 100 exposed edges may rest upon plate 18 in scraping relation thereto. At its large end, the body portion is provided with a transverse wall 27 terminating a distance above plate 18 in an angular flange 28 adapted to be engaged under a plate 13 105 of the conveyer chain. At the top of wall 27 there is formed a flange 29 parallel to flange 28 and adapted to overlie a plate 12 of the chain. The flanges 28 and 29 are provided with apertures registering with the aligned apertures, above de- 110

scribed, of plates 12 and 13 and the bolts 23 and 24 are passed through the apertures to connect the flight and link. The projecting portions of plates 12 and 13 are in such proximity to the outer 5 face of wall 27 as to abut the latter and prevent substantial swinging of the flight if the bolt at the trailing side of the flight should become broken. One bolt at the leading side of the flight is sufficient to secure the latter in operative position due 10 to the described cooperability of the link-plates with wall 27. As shown in Fig. 3, the space between flange 28 and the base-plate is sufficient to provide ample clearance between the latter and the bolt heads.

15 At the tapered end of the body portion is a flat foot portion 30 whose lower surface lies in the plane of the exposed lateral edges of the body portion. Formed on the third lateral edge of the body portion and extending centrally of the foot portion 20 30, is a fin 31 in a plane substantially perpendicular to the longitudinal line of the conveyer chain and declined from the latter to the foot portion. The upper edge of fin 31 is provided with serrations as at 32. The tapered form of the flight 25 gives it great strength and permits it to engage itself readily under masses of material to be conveyed, while the fin is adapted to disrupt material only partially disintegrated, and also serves to increase the strength and carrying capacity of 30 the flight. The form of the flight is particularly advantageous when the flight is intended for use in a gathering conveyer such as has been described in my above mentioned application. According to the disclosure of that application, the gathering 35 conveyer is adapted to be sumped longitudinally or swung laterally into engagement with disrupted coal, the flights clearing a path for themselves and propelling the coal toward the head of the conveyer.

40 In the modified form of flight shown in Figure 4, the hollow portion of the body 26' is of somewhat greater longitudinal extent in proportion to the total length of the flight, the body portion terminating in a short foot portion 30'. The declination of the top of the flight is thus considerably less abrupt than in the embodiment first described. The fin 31' is relatively low so that the serrations 32' extend substantially down to the body portion. The teeth, it will be noted, are 45 faced toward the inner end of the flight, their inner edges being at about thirty degrees to perpendicular lines passing through their apices and their upper edges being at about forty-five degrees to such lines. The inner edges of the teeth 50 are substantially perpendicular to the inclined top portion of the flight body, the angle at the apex or point of each tooth being about seventy-five degrees, or somewhat less than a right angle.

55 Due to the described arrangement and relation of parts, the flight just described has a particularly effective action in lifting up the material to be transported, dragging it on the conveyer, and disrupting bulky masses.

It will be understood that I do not limit myself 60 to the exact details of structure shown and described, the following claims being determinative of the scope of the invention.

I claim:

1. In combination, a conveyer chain comprising 65 a link composed of a pair of parallel plates provided at one side of the chain with oppositely projecting flanges adapted to be engaged in opposite guide grooves, said plates projecting beyond the other side of the chain and having their projecting portions provided with aligned apertures, a

flight having flanges overlying said projecting portions, the flanges having apertures registering with the first named apertures, and pins passed through the apertures to connect the flight and link in rigid relation.

2. A conveyer flight of elongated form adapted to be propelled along and over a supporting surface, said flight having a substantially rectilinear bottom edge for scraping contact with the said surface and being declined longitudinally to a relatively thin freely projecting extremity, said flight having a top longitudinal edge provided with serrations.

3. A conveyer flight comprising a substantially triangular pyramidal body portion, a serrated fin extending along one of the lateral edges of the body portion, and means at the base end of said body portion adapted to be secured to a draft device to position said fin in a plane substantially perpendicular to the longitudinal line of said draft device.

4. A conveyer flight comprising a substantially triangular pyramidal body portion having at its apex a spade-like prolongation in the plane defined by two of its lateral edges, a fin extending 100 along the other lateral edge of said body portion and along said prolongation, and means at the base end of said body portion adapted to be secured to a draft device to position said fin in a plane substantially perpendicular to the longitudinal line of said draft device.

5. A conveyer flight comprising a substantially triangular pyramidal body portion having at its apex a spade-like prolongation in the plane defined by two of its lateral edges, a serrated fin 110 extending along the other lateral edge of said body portion and along said prolongation, and means at the base end of said body portion adapted to be secured to a draft device to position said fin in a plane substantially perpendicular to the longitudinal line of said draft device.

6. A conveyer flight comprising a normally horizontally extending elongated body portion adapted for attachment at one end to a motive element with its other end in freely projecting relation, the top of said flight being declined from said one end to the other end, and a series of alined substantially triangular teeth extending longitudinally of the top of the flight.

7. A conveyer flight comprising a normally 125 horizontally extending elongated body portion adapted for attachment at one end to a motive element with its other end in freely projecting relation, the top of said flight being declined from said one end to the other end, and a series 130 of alined substantially triangular teeth extending longitudinally of the top of the flight, said teeth presenting edges substantially perpendicular to the inclined top of the flight and faced toward the attached end of the flight.

8. A conveyer flight comprising a normally horizontally extending elongated body portion adapted for attachment at one end to a motive element with its other end in freely projecting relation, the top of said flight being declined 140 from said one end to the other end, and a series of alined substantially triangular teeth extending longitudinally of the top of the flight, said teeth presenting edges substantially perpendicular to the inclined top of the flight, and faced toward the attached end of the flight, the apex angle of each tooth being somewhat less than a right angle.

9. In combination, a conveyer chain comprising 145 links, each composed of a pair of parallel

- plates provided at one side of the chain with oppositely projecting flanges adapted to be engaged in opposed guide grooves and at the other side with aligned apertures, a flight having flanges 5 provided with apertures registering with the first-named apertures, pins passed through the registering apertures to connect the flight and link, the plates of each link being provided with aligned pintle receiving apertures intermediate the first-named apertures and said oppositely projecting flanges, blocks having apertures registering with the adjacent pintle-receiving apertures of adjacent links, and pintles connecting the blocks and links, each of said blocks being articulated on an 10 axis extending transversely of the pintles. 80
10. In combination, a conveyer chain comprising links, each composed of a pair of parallel plates provided at one side of the chain with oppositely projecting flanges adapted to be engaged in opposed guide grooves and at the other side with aligned apertures, a flight having flanges 15
11. A conveyer flight of elongated form adapted to be propelled along and over a supporting surface, said flight being declined longitudinally to a relatively thin freely projecting extremity 90 and having a top longitudinal edge provided with serrations, the flight having a front surface forwardly declined to a bottom edge adapted for scraping contact with said surface. 95
